UNITED STATES PATENT OFFICE.

MORTIMER L. PACKER, OF COLUMBUS, OHIO.

COMBINED HEATING AND ILLUMINATING BURNER.

1,074,560.

Specification of Letters Patent. Patented Sept. 30, 1913.

Application filed February 1, 1912. Serial No. 674,762.

To all whom it may concern:

Be it known that I, MORTIMER L. PACKER, a citizen of the United States, residing at Columbus, in the county of Franklin and 5 State of Ohio, have invented certain new and useful Improvements in Combined Heating and Illuminating Burners, of which the following is a specification.

My invention relates to combined heating 10 and illuminating burners and contemplates the provision of a structure of attachment of this nature which is peculiarly formed to obtain a maximum degree of heat by the flame maintained and to have the continuous 15 and automatic operation of the burner such as to preclude oxidation of the light diffusing and reflecting and deflecting surfaces. In the attainment of this result, it is important that the heating effect be not sacrificed. 20 I have taken care of this and at the same time I have utilized the normal heat of the burner to draw in a current of air which is so directed and diffused as to form a layer intermediate any reflecting and deflecting 25 surfaces of the burner and the heating flame. The tendency, therefore, is generally to deflect the flame downwardly or if this is not done to form a layer of comparatively cold air between the deflecting surfaces and the 30 flame as stated.

My invention may be embodied in a burner having an annular series of gas jets with a plurality of air passages having their outlets near the said gas jets and desirably 35 at a point slightly above the same. The heat of the gas jets is desirably rendered effective to produce a natural draft of the air into the passages and the continued heating of the air inevitably causing the rising thereof 40 within the structure of the burner, is such as to cause the volume of air issuing from the passages to spread into a thin layer above the heat waves emitted from the flames of the gas jets and just below the main deflecting and reflecting plate or element of 45 the burner. The main reflecting and deflecting plate is desirably a portion of the hood structure mounted above the gas jets and although such hood is sufficiently perforated 50 to support combustion, it nevertheless sufficiently incloses the gas jets and the flames produced thereby to receive the heat waves upon its vertical walls and radiate the heat therefrom into the room. Thus, the light

produced is maintained at a high standard 55 while the heat radiation is still undiminished. Not only do these apertures assist in creating a proper draft, but they serve as a means of escape for a certain portion of the heat to prevent smothering of the flame. 60

The preferred embodiment of my invention is shown in the accompanying drawings, in which similar characters of reference designate corresponding parts, and in which—

Figure 1 is a side elevation of my attachment, Fig. 2 is a section taken on line 2—2 of Fig. 1, and, Fig. 3 is a detail of a wall guard desirably utilized in connection with my improvement.

In carrying out my invention, I provide a hood structure having a disk-like upper portion 1, the under surface of which is preferably highly polished to serve both as a reflecting and deflecting surface 2, and a 75 circular depending wall 3 preferably apertured as shown at 4 for a purpose to be hereinafter described.

Depending from the central disk-like formation 1 and secured thereto by lugs 5 is 80 an annular or ring-shaped element 6 having a plurality of gas jets 7 formed therein and leading from an annular chamber 8. This annular chamber 8 is fed from a T-shaped passage comprised of the ducts 9 and 10 85 communicating at a central point with the vertically extending pipe 11. This vertically extending pipe 11 is externally threaded at its upper end and adapted to screw into an integral formation 12 upon such 90 ring-shaped element. At its lower end the pipe 11 is likewise externally threaded and by means of such external threads supports a valve structure 13 comprising a body portion 14, a bracket yoke 15, an internally 95 threaded bore 16 and an intersecting bore 17 within which operates a valve 18. The bracket yoke 15 is formed with an annular shoulder 19 at its upper edge and upon such annular shoulder 19 there rests a tubular 100 formation 21 which embraces the pipe 11 and is disposed in concentric relation thereto. This tubular formation 21 serves as an air feed leading to the space between the diametrical formation 12 of the ring member 6 105 and the inner periphery thereof.

In conjunction with my hood structure, I may utilize a swinging guard bracket com-

- prising an arm 22 pivotally secured as at 23 to a central point upon the upper surface of the disk 1 and extending upwardly and outwardly to the outer periphery of the hood. This arm 22 may extend to any desired distance beyond the outer periphery of the hood and is desirably bent down and secured as at 24 to an arcuate metallic guard plate 25 having its inner surface covered by an asbestos sheet 26. The height of these sheets is immaterial, but it is preferable that it be at least the same height as the hood and thereby calculated to protect any object in line with a certain portion of the hood.
- 15 In operation it will be understood that the device is attached to a gas cock by means of the internal bore 16 and when the valve 18 is open, gas passes up the pipe 11, into the formation 12 and into the annular chamber 20 8, thence being emitted from the gas jet 7. In the meantime, air is drawn upwardly into the tubular formation 21 because of the comparatively heated condition of the upper portion of my device and passes through the 25 passages 27 and 28 formed by the structure of the ring member and the diametrical formation. After passing through these passages, the air inevitably spreads and taking the line of least resistance, passes radially 30 outward in all directions under the effect of the draft created through the apertures 4. In this passage of the air radially outward it forms a layer next to the inner surface of the upper wall 2 of the hood which is polished to a bright reflecting surface and by forming such inner layer, prevents a collection 35 of carbon thereon from the flame which is spreading radially there beneath in its emission from the gas jets. The flames from 40 the gas jets, then, are maintained substantially in a straight line by means of this layer of air or they may be forced to assume a slightly downward trend or curvature. They are maintained in condition of life by 45 the apertures 4 in the side wall 3 of the hood, which serves to create a sufficient through draft and to prevent choking of the flame by too great an assemblage of heat waves within the hood. The beams of 50 light and the heat from the flames are therefore reflected and deflected downwardly and outwardly into the room because of the peculiarly formed upper wall, whose inner surface is a reflecting surface, while the heat 55 currents which do not pass through the apertures of the side walls of the hood, strike against such side walls and cause a radiation of the heat therefrom throughout the room.
- 60 The valve 18 is particularly advantageous because it provides a means for maintaining an initial inflow of the gas when the cock is open. The valve 18 is desirably ordinarily set to the proper point and consequently 65 though the cock may be turned on full, the

flame in the burner will not be excessive. Actual experience has demonstrated that it is desirable to guard against an excessive flame, for the reason that the flame may become sufficiently great to pass through the 70 apertures in the side walls of the hood. As a further safeguard against any adjacent objects, the burner is provided with the arcuate pivoted element described which may be shoved to any position to guard any 75 article which may be within range.

What I claim, is—

1. A heat and light radiating gas burner comprising a hood, a hollow fuel chamber having an annular series of radially disposed gas jets, a central feed pipe for feeding gas to said fuel chamber and a concentric pipe having an outlet above said gas jets and within the outer periphery of said fuel chamber.

2. A heat and light radiating gas burner comprising a hood having a plurality of apertures in its side wall and having its upper internal surface formed of reflecting material, a hollow fuel chamber having an annular series of radially disposed gas ports and centrally mounted within said hood, a central feed pipe for feeding gas to said fuel chamber, and a concentric air pipe having an outlet above said gas jets and within the outer periphery of said fuel chamber.

3. In combination with a hood structure for a heat and light radiating gas burner, a gas burner element proper having a series of gas outlet ports, said burner proper being constructed to permit the flowing of a layer of air between the radiating surface of said hood structure and the gas flame from said ports.

4. In combination with a hood structure for a heat and light radiating gas burner, a gas burner element proper having a series of gas outlet ports along its outer periphery and having an air outlet port inward of and above said gas ports.

5. In combination with a hood structure for a heat and light radiating gas burner, a gas burner element proper comprising a casting having an annular series of gas outlet ports and having an air outlet concentric with, but of less diameter, and above said gas ports.

6. In combination with a hood structure for a heat and light radiating gas burner, a gas burner element proper comprising a casting spaced from said hood structure and formed with an annular chamber having gas outlet ports, a gas supply pipe connected with said chamber, said casting having an open top, and an air supply pipe in communication with said open top.

7. In combination with a hood structure for a heat and light radiating gas burner, the depending sides of said hood structure being apertured, a gas burner element

proper comprising a casting attached to but being spaced from said hood structure and being formed with an annular chamber having radial gas outlet ports, a central gas supply pipe connected with said chamber, said casting having an open top, and an air supply pipe surrounding said gas pipe and in communication with the open portion of

said casting whereby an air draft is created between said opening and said apertures. 10

In testimony whereof I affix my signature in presence of two witnesses.
